UNITED STATES PATENT OFFICE.

JAMES POLLOCK, OF NEW YORK, N. Y.

APPARATUS FOR BURNING FINE FUEL IN SUSPENSION.

Application filed September 13, 1926. Serial No. 135,222.

This invention relates to furnaces for burning fine fuel, such as coal dust, in suspension. In my Patent No. 1,580,321, dated March 17, 1925, I have shown a furnace of this type in which air and fuel are blown upwardly in an upwardly enlarging combustion chamber, and the fuel is held in suspension until consumed. The fuel is ignited by oil burners, but after the furnace has become well heated the burners are extinguished and the fresh fuel blown into the chamber mingles with the incandescent fuel already in the chamber and is ignited and consumed. To promote combustion, air is admitted at various points in the height of the furnace, the pressure and volume of air being controlled so as to supply what air is needed for complete combustion without causing such an increase in pressure as would force unburned fuel particles out at the top of the chamber.

It is found to be of very material advantage, in this type of furnace, to preheat the air admitted to the combustion chamber, because cold air blown in tends to chill the fine incandescent particles of fuel and to hinder combustion. In the present invention, therefore, I have provided a preheater for the air, arranged in the furnace stack so as to utilize the heat in the stack which would otherwise be wasted, and this preheated air is blown into the furnace chamber, thus avoiding the chilling effect of cold air on the incandescent fuel and conserving a considerable amount of heat energy.

It is important in this type of furnace to retain the fine fuel in the furnace chamber until consumed, and therefore it is desirable not only to avoid such internal pressure in the chamber as would force unconsumed particles out at the top, but it is necessary to avoid having a relatively low pressure in the flue leading to the stack, as this would have the same effect. In my Patent No. 1,606,719 dated November 9, 1926, I have shown a furnace with a stack which is relatively short in order not to create a strong draft, and means for regulating the flow of gases to the stack, so as to retain a balanced pressure in the furnace chamber. The draft through the stack is influenced by the wind blowing past the stack, and also by barometric pressure. I have, therefore, in the present invention, arranged a damper at the outlet of the stack, to adjust the size of the outlet, and also a wind shield which is adjustable with the

damper and surrounds the opening to prevent the draft from being affected by changing atmospheric conditions.

In the accompanying drawing,

Fig. 1 is a longitudinal central section through the furnace, partly broken away; and,

Fig. 2 is a central vertical section through the stack and air heater, partly broken away and on a larger scale than is shown in Fig. 1.

Referring to the drawing, *a* indicates a combustion chamber of the kind shown in my prior patent, this chamber enlarging gradually from the bottom to the top, and *b* indicates a flue leading downwardly from the top of the combustion chamber into a chamber *c*, containing a tubular boiler *d*, and the chamber *c* communicates through passageway *e* with a relatively short cylindrical stack *f*. Within the stack is arranged a preheater *g*, for preheating the air which is supplied to the furnace. A fan *h* is shown for forcing air into the upper end of the preheater through a pipe 1, and from the lower end of the preheater a pipe 2 extends to a point adjacent the furnace chamber *a*. A pipe 3 extends from the pipe 2 to a nozzle 4, arranged at the lower end of the furnace chamber and adapted to direct the air upwardly in said chamber. Several branch pipes 5, 6 and 7 are shown connected to the pipe 2 and opening into the furnace chamber at various points in the height of the latter. Fine fuel is fed to the nozzle 4 through a pipe 8, by suitable feed mechanism, the details of which are not shown. As in my former patent, oil or gas burners are arranged in the lower part of the furnace chamber for initially igniting the fuel, one of these burners being indicated at 9, Fig. 1.

The preheater *g* comprises two hollow circular drums or heads 10 and 11, and the pipes 1 and 2 communicate with these heads, respectively. The heads are connected together by tubes 12, through which the air may pass from one head to another. These tubes fit within the casing of the stack *f*, and the head 10 is supported a short distance above the upper end *f'* of the stack. The stack is cylindrical and upon its upper end is slidably mounted an annular damper *j*, which is supported by several adjustable rods 13 and movable to enlarge and restrict the annular gap *k*, between the top of the stack and the head 10 of the preheater. The rods are shown extending through brackets

14 on the lower part of the stack, and the lower ends of the rods are threaded and provided with nuts 15, by which the rods may be adjusted vertically. By adjusting 5 the damper upwardly the gap through which the gases flow will be restricted, and by adjusting the damper downwardly the width of the gap will be increased to permit a freer flow of the gases. By regulating the 10 volume and pressure of air admitted to the furnace chamber, and by regulating the width of the gap k , the pressure in the furnace chamber may be balanced so that the fuel projected upwardly through the nozzle 15 4 will be held in suspension until entirely consumed.

As the draft through the stack would be affected by wind blowing over the top of the stack and through the gap k , I have 20 provided an annular wind shield m , which is secured to the damper but spaced from it, as shown, and this shield projects above the damper and also above the header 10 when the damper is partly raised. Thus, the wind 25 cannot blow through the gap k . If strong winds prevail the damper and shield may both be raised so as to lower the aspirating effect of the wind in blowing over the top of the stack, and when the weather is calm, 30 the shield and damper may be lowered to permit the gases to flow out more freely by the internal pressure. As the flow of gases through the stack to the atmosphere is also affected by barometric pressure, the damper 35 may be raised or lowered to compensate for changes in atmospheric pressure.

What I claim is:

1. In an apparatus for burning fine fuel in suspension, a furnace chamber, a relatively low stack and passageways connecting 40

the top of the chamber with the lower part of the stack, an air heater in the stack having a hollow head extending over the stack and spaced from the same, leaving an annular gap for the escape of gases, an annular damper slideable vertically upon the stack for varying the width of said gap, and means for blowing air through the heater into the furnace chamber. 45

2. In an apparatus for burning fine fuel 50 in suspension, a furnace chamber, a relatively low stack and passageways connecting the top of the chamber with the lower part of the stack, an air heater in the stack having a hollow head extending over the stack 55 and spaced from the same, leaving an annular gap for the escape of gases, an annular damper slideable vertically upon the stack for varying the width of said gap, an annular windshield of larger diameter than 60 the damper secured to the damper and projecting above the same, said shield being movable with the damper, and means for blowing air through the heater into the 65 furnace chamber.

3. In an apparatus for burning fuel, a furnace chamber, a stack and passageways connecting the chamber with the lower part of the stack, an air heater in the stack having a hollow head extending over the stack 70 and spaced from the same, leaving an annular gap for the escape of gases, an annular damper slideable vertically upon the stack for varying the width of said gap, and means for blowing air through the heater 75 into the furnace chamber.

In testimony whereof I hereunto affix my signature.

JAMES POLLOCK.
